UNITED STATES PATENT OFFICE.

JAMES F. DUNLEAVY, OF NEWTON, MASSACHUSETTS.

TAB FOR INDEX-CARDS.

1,077,334.

Specification of Letters Patent.

Patented Nov. 4, 1913.

Application filed December 18, 1912. Serial No. 737,382.

To all whom it may concern:

Be it known that I, JAMES FRANK DUNLEAVY, a citizen of the United States, residing at Newton, in the county of Middlesex and State of Massachusetts, have invented new and useful Improvements in Tabs for Index-Cards, of which the following is a specification.

My invention is an improved tab to be applied to cards used in card indexes.

In the drawings: Figure 1 is a view of a card cut to receive my new tab; Fig. 2 is a side view of one part of my tab; Fig. 3 is a plan view of another part of my tab; Fig. 4 a view of the card with my new tab applied; Fig. 5 is a plan view of a modification of the retainer band.

It has heretofore been practised to form a tab upon the upper edge of an index card, integral with the card, but this method, inasmuch as the tab was integral with the card, made it impracticable to apply the index words or letters to a tab before the position of the tab upon the card had been determined by the necessities of the particular system ordered. In consequence, in practice, the placing upon cards of the index words or letters was done one card at a time, when the position of the proposed tab had been determined, in view of the cards which were to precede and follow the particular card and the upper edge of the card was then cut away, by dies or otherwise, to leave the tab portion with its lettering projecting above the body of the completed card.

My improved tab is made distinct and extrinsic from the card with which it is to be used and the card can consequently be cut at the outset to its finished size and need not, as is the case with cards designed to carry an integral tab, be cut with a margin as wide as the proposed tab is high, nearly all of which margin is wasted when the tab is formed by the die. This is a very considerable saving of stock. Again, in making up all card index systems for different uses the index tabs differ in lettering, position and number, according to specific requirements. Where the tab is integral with the card these tabs cannot be printed or formed until the position of a particular tab is determined, while when the tab is extrinsic tabs may be printed in sheets, cut and kept in stock ready for application as needed.

In carrying out my invention I form the index part of the tab, preferably, of cellul-

loid, as this is non-absorbent, waterproof and easily kept clean and is more wear resisting than cardboard, and I preferably form it substantially of the shape shown in the drawings, the portion 1 above the dotted line *a* forming the index, the part 2 an anchor to engage a corresponding perforation in the upper side of the card, and part 3 a neck connecting the part 2 to the body of the tab and the part 4 below the dotted line serving for a purpose hereinafter described.

In connection with the part of the tab shown in Fig. 2 I form a retainer 5 having a medial slot 55, the slot being as wide as the thickness of the card and of the part 1 and of a length equal to the extreme length of part 1. The card, A, is preferably cut as shown in Fig. 1, the cut consisting of three parts, viz., a recess *a*, along the upper edge of the card, which is equal in length and depth to the portion, 4, of the tab body, a perforation *b* and a neck *c* connecting the perforation with the recess *a*. The tabs and retainer bands are designed to be made up in standard sizes and may be printed in advance with any desired inscriptions and may be printed in sheets of any required size and died out economically.

When it is desired to make up a system to a particular order as is the common practice, having determined where the tabs shall be positioned upon the cards making up the system, a number of blank cards can be at one operation punched at the proper place along the upper edges of the cards, as indicated in Fig. 1. The desired index tab is then inserted in the perforation, *a*, *b*, *c*, the projecting portions 2, 3, 4 fitting respectively within the recess *b*, *c*, *a*, and the part 1 of the tab projecting above the upper edge of the card. The retainer portion 5 of the tab is passed over the index part 1, the part projecting through the slot 55 and the edges of the retainer band are folded down over the upper edge of the card, covering the projecting anchor ends 44 of the tab body as well as the parts, 2, 3, 4. The retainer, 5, is suitably cemented on both sides of the card and when this is accomplished the tab will become substantially integral with the card to which it is applied and will be restrained from movement in any direction, the projections *p*, *p*, and the retainer band above the projections 44 restraining any upward movement of the index tab, the parts 4, 3, 2 in cooperation with the retainer band

5 preventing any crosswise movement of the tab and the card itself preventing any longitudinal movement of the tab.

The use of the projection 2 as an anchor part instead of relying solely upon the projections 44, has the advantage that, when the tab 1 which projects as a handle or lever, above the edge of the slot 55, is handled in use, any cross strain is met by ample leverage upon the opposite side of what is in effect a fulcrum, viz., the edge of the slot 55, and strength against such cross strains is provided by the width of the index tab at the fulcrum point where any tendency to bend or break will be concentrated.

The index portion 1, of the tab, together with its appurtenant parts 2, 3, 4, will be made of celluloid, for the reasons already set forth, but preferably, the retainer 5 will be made of tough thin fibrous material, of the same color as the card, so that when adhesively applied it will support the index part of the tab and connect and anchor together all parts of the tab and card and at the same time will cover and conceal the anchor portions of the index tab. The anchor portions of the index tab may be varied greatly, and serve to make every part of the index card coöperate with every other part to produce a practically unitary card.

The use of the two different materials mentioned above for the two parts of the tab is in most cases to be preferred, since the celluloid index portion is almost perfect for the purpose to which it is applied,

in permanence and appearance, while the tough paper stock, as applied in the retainer band, links all the parts more firmly and securely by suitable cement, covers the joint from sight and is withal cheaper than 40 would be a retainer of celluloid.

Under certain conditions it is desirable that the index portion of the tab should be covered, and when this is desired the retainer 5 is formed substantially as shown 45 in Fig. 5, so that when folded on line 5^a it may be applied to surround and cover the upwardly projecting portion of the tab. If desired when so applied, the retainer may be made of this transparent material, thus 50 permitting the index letters to be visible.

I claim:—

1. The index card above described, recessed on its upper edge to receive the lower side of the index tab; the tab within said 55 recess; and a retaining strip to engage and connect the index tab and the card.

2. The two-part tab above described, made up of a body part with a projecting anchor portion shaped to fit into a recess 60 in the upper edge of an index card and a retaining band adapted to engage and connect the tab and card.

Signed by me at Boston, Massachusetts, this fourth day of December, 1912.

JAMES F. DUNLEAVY.
